UNITED STATES PATENT OFFICE.

CHARLES E. JOHNSON, OF MUSKEGON, MICHIGAN, ASSIGNOR TO MUSKEGON MOTOR SPECIALTIES COMPANY, OF MUSKEGON, MICHIGAN.

MICROMETER.

972,196.

Specification of Letters Patent. Patented Oct. 11, 1910.

Application filed April 9, 1910. Serial No. 554,563.

To all whom it may concern:

Be it known that I, CHARLES E. JOHNSON, a citizen of the United States, residing at Muskegon, in the county of Muskegon and 5 State of Michigan, have invented certain new and useful Improvements in Micrometers, of which the following is a specification.

My invention relates to improvements in implements for measuring very small differences in the size or diameter of objects for the purpose of determining to the minutest fraction of an inch, the diameter or dimensions of an object, and its objects are: First, to provide a micrometer that may be so connected with a lathe or grinding machine as to determine the smallest possible fraction of an inch of difference in the diameter of any shaft or other object being worked thereon. Second, to provide a micrometer or implement of the kind stated with which a shaft having an uneven surface may be ground to the exact dimensions and proportions desired without being taken from the grinding machine and without stopping the machine. 25 Third, to provide an implement of the kind stated with which the minutest imperfections in the surface of shaft, or other article being ground, may be instantly detected without stopping the machine. I attain these objects by the mechanism illustrated in the accompanying drawing, in which—

Figure 1 is a side elevation of the micrometer shown upon a grinding machine with the working parts cut off on the line 1—1 of Fig. 3. Fig. 2 is a plan of a grinding machine with the micrometer attached. Fig. 3 is an elevation of the same. Fig. 4 is a side elevation of the micrometer showing an exceedingly fine adjusting mechanism for turning perfectly round rods. Fig. 5 is a front elevation of the same, and Fig. 6 is a front elevation of the same as constructed for making measurements upon rods or shafts having uneven surfaces.

Similar letters refer to similar parts throughout the several views.

This implement consists of a lower, permanent arm A that I prefer to have made integral with a semicircular bearing portion C' to which the handle C is secured. The bearing portion C' is adapted to rest freely upon a guiding rod D so that the implement may be rocked freely up and down, with this rod 55 as a pivot point. To the arm A is pivoted a

second arm, B, as at a, in such a manner that the outer ends of the arms, as at H H, may be made to recede from or approach each other as the surface of the object being worked may vary.

H H represent two thoroughly hardened jaws that are secured into or onto the ends of the arms A and B in position to properly caliper a shaft or rod, as L, that is being ground. These jaws H, H, are made adjustable as indicated by the slots h so that they may be adjusted to various sizes of shafts or rods L, and the two arms are actuated to draw the jaws H H strongly toward each other by any available form of spring, that shown at E in Figs. 1 and 4, being preferred.

The arm B has, mounted thereon, a standard F which has a segment, F', formed at its upper end, which segment is graduated with a very fine, accurate scale whereby the diameter or dimension of an object, as L, may be determined to the thousandth of an inch, or less, by noting the position of the end of the needle or index G upon the segment, and this needle is made sensitive to the slightest possible imperfection in the surface of L as follows:—The needle is pivotally supported on the arm B, substantially as indicated at G', and has a short lug or arm, as g, projecting out to one side of the pivotal line. This arm rests upon the upper end of a small pointed needle K, the other end of which rests upon the long end of the lever I or I'. The lever I is pivotally supported upon a standard J, as at j, and the short end of this lever receives the fine point of the bearing b, or its equivalent, as at i', so that any variation in the surface of the shaft L, as it is turning between the jaws H H, is greatly magnified by the movement of the needle G upon the dial or segment F', so that the movement of the jaws H H the one thousandth of an inch, or even one half that distance, will be readily detected and measured on the scale on the segment F', and as the operator always stands in position to easily manipulate the handle C of the micrometer he is, necessarily, in position to easily note every movement of the needle G, and thus always able to determine the exact variation, if any, that exists in the surface of the shaft L, as it revolves, and is being acted upon by the fast revolving emery wheel M.

As the operation of grinding machines is

well known by those versed in the art, and as they do not enter, in any way, into the direct operation of my invention, I will not make any attempt at describing one, and 5 simply show parts of one form of these machines for the purpose of illustrating the action of this micrometer.

When turning and measuring a perfectly round shaft, as L' in Figs. 4 and 5, I generally provide a very fine, nice adjustment by using a needle, as K', between the end of the set screw, or adjusting screw b' and the end of the lever I', which is allowable as there is no danger of either of the needles, K 10 or K', dropping out of place by reason of great variation of the movement of the jaws H H, but when turning shafts that have a considerable variation in the surface, as, for instance, the shaft L shown in Figs. 1 and 6, 15 which have a cam or projection, as l, on one side, it is necessary to provide some means for allowing said projection to pass, with the shaft, between the jaws H H without danger of disarranging the bearing points 20 and pieces. As, for instance, to throw the jaws as far apart as would be necessary in the action shown in Fig. 6, the needle K' would be carried so far by the end of the lever I' that it would drop out of the arm B 25 and cause great annoyance. To obviate this I place a long set-screw, as b, in the arm B, that I can adjust to any position necessary for the proper actuating of the lever I; and it is designed to have sufficient length 30 through the arm B to avert all danger of the needle K becoming disengaged from its bearing at i on the long end of the lever I or I'.

When using this micrometer for turning 35 a shaft with a cam, as l, on one side, it is necessary to make the bearing at C' broad enough to hold the micrometer to a perfect perpendicular position, as it is necessary to make the lower jaw H as thin as possible, 40 hence I mortise a thin plate H into the end of the jaw A, as in Fig. 6, but when turning a perfectly straight shaft the lower jaws may be wider, and for this purpose a plate, H', may be placed on each side of the end 45 of the arm A, as indicated in Fig. 5, which will aid greatly to hold the micrometer to proper position.

When using the form of spring shown in 50 the several views, for drawing the arms A and B toward each other, it is necessary to form some kind of integral lugs, as e, upon

the arms, for the spring to act upon, as indicated in Figs. 1 and 4.

The lug or arm g, that controls the movement of the needle G may be held in contact with the needle K by means of a very delicate spring, as g', shown in Fig. 1.

What I claim as new, and desire to secure by Letters Patent of the United States, is:

1. In a micrometer, a permanent arm, an arm pivotally connected therewith, a spring for holding said arms to normal position, a handle on the permanent arm, a guide way between the handle and the pivot point between the arms, adjustable jaws at the ends of the arms, a standard having an indexed segment at its end, a finger parallel with the standard, a lever secured between the arms, and connections between the arms and said lever, and between the lever and the finger for actuating the finger.

2. In a micrometer, two arms pivoted together near one end, a spring for holding said arms to normal position, a handle connected with one of said arms, a bearing surface between the handle and the arms, jaws connected with the other ends of the arms, a standard on one arm having an indexed segment at its upper end, a finger pivotally supported on the arm parallel with the standard, a short arm at right angles with said finger, a lever pivotally supported from the lower arm, a needle between said lever and the short arm on the finger, and a connection between said lever and the upper arm of the micrometer, all arranged to actuate the finger by the movement of the jaws and arms and to greatly increase said movement at the end of said finger.

3. In a micrometer, a permanent arm, a movable arm pivoted thereto, jaws in the free ends of said arms, means for holding said arms to normal position, a standard on the movable arm, a finger pivoted on said arm to stand parallel with the standard, a lever pivotally supported between the arms, an adjusting screw, and a needle connected with said lever for actuating said finger one way, and a spring for actuating it the other way for fine measurements.

Signed at Muskegon Michigan March 26 1910.

CHARLES E. JOHNSON.
